No. 8,571.

PATENTED DEC. 2, 1851.

R. WINANS,
RUNNING GEAR FOR LOCOMOTIVES.

Inventor,

R. Winans

UNITED STATES PATENT OFFICE.

ROSS WINANS, OF BALTIMORE, MARYLAND.

RUNNING-GEAR OF LOCOMOTIVES.

Specification of Letters Patent No. 8,571, dated December 2, 1851.

To all whom it may concern:

Be it known that I, ROSS WINANS, of the city of Baltimore, in the State of Maryland, have invented a new and useful Improvement 5 in Locomotive-Engines to be used on Railroads; and I do hereby declare that the following is a full and exact description of the same.

The drawing annexed Figures 1 and 2 illustrates and forms a part of this specification. It represents a passenger engine of 10 large class, the total weight of which is from 22 to 25 tons. It has eight small supporting wheels, arranged in two separate 15 four wheel trucks of any desirable description, the trucks swivel or turn upon their own centers, similar to those of an eight wheeled car, and are arranged under the engine with a view to the proper distribution 20 and support of its weight on the road. Fig. 1 represents a side view of the engine, with a single pair of large driving wheels, seven feet in diameter. Directly over the journals of the axles of these wheels, are 25 placed, and secured to the boiler, two steam cylinders W, W, W, Figs. 1 and 2, one on each side of the boiler. These cylinders are of cup form and have their open ends provided with a stuffing box and gland, see section 30 Fig. 2, like the ends of the pump barrels of a locomotive engine into which the pump plungers play. These cylinders are placed with their open or stuffing box ends downward. Into them are fitted the cup or 35 tumbler formed plungers or pistons P, P, Fig. 2, with their open ends also downward. When these pistons are in place, the stuffing boxes of the cylinders are packed with hemp or other suitable substance, so as to form a 40 steam tight joint between the plunger and the stuffing box.

G, G, Fig. 2, are two bars or bolts of iron, one of which is shown at G, Fig. 1. The upper ends of the bars bear against the center of the heads of the cup formed plungers P, P, as shown in section at Y, Y, Fig. 2. The lower ends rest on the center of the bearing box on the axle of the driving 45 wheels in the manner of the ordinary spring 50 bolts of engines.

When steam is let into the cylinders above the plungers, (constructed and arranged as described) the driving wheels of the engine are pressed down to the rails of the road 55 with an amount of force proportional to the

pressure of steam acting upon the ends, or areas of the steam plungers or pistons, and as this forcing of the driving wheels down upon the rails is increased in amount or weight, so is the adhesion of the driving 60 wheels to the rails increased, and this adhesion being the only fulcrum by which the moving power acts to give motion to the engine, and its load, the tractive force which the engine can exert is increased in the same 65 ratio. When no steam is let into these cylinders the driving wheels propel the engine upon the rails only through their own weight, and that of their axles, eccentrics, &c., but support no part of the boiler until 70 steam is admitted into the cylinders above the said plungers or pistons. The arrangement I prefer for letting steam into these adhesion cylinders is by means of a communication between them and the main steam 75 pipe leading from the throttle valve to the main propelling cylinders, as shown at a, a, Fig. 2. By this arrangement the throttle valve, which is used for the purpose of regulating the pressure of steam admitted into 80 the main or propelling cylinders of a locomotive engine, will also in a nearly corresponding degree regulate the pressure of steam in the adhesion cylinders. The plungers or pistons upon which the steam acts to 85 obtain the requisite adhesion are to have such an area as, when acted upon by the maximum pressure of steam proposed to be used in the boiler, shall cause the wheels to be pressed down to the rails with a force 90 which, when added to the weight of the wheels, axles, eccentrics, &c., will be equal to the greatest weight which it is proposed to apply on the drivers for the purpose of obtaining the adhesion upon which the tractive 95 power of the engine depends. This being determined, the main or propelling cylinders are to be made of such capacity as shall with the maximum pressure of the steam render available the adhesion due to the 100 maximum weight on the drivers, to the fullest practical intent. The following dimensions of the engine here represented it is believed will answer well in practice with a maximum pressure of steam of eighty 105 pounds per square inch: Propelling cylinders, 17 inches diameter; stroke of piston, 22 inches; driving wheel, 7 feet diameter; pistons of adhesion cylinders, 11 inches diameter.

- The areas of the adhesion pistons are equal to 190 square inches. With this area of piston, and with 80 pounds per square inch as the maximum pressure of the steam in the adhesion cylinders, the driving wheels will be pressed down to the rails with a force of 15,200 pounds. Add to this the weight of the wheels, axles, eccentrics, &c., 7,300 pounds, and we have a weight on the drivers of 22,500 pounds, or 10 tons, which is perhaps as great a weight as should be admitted on a single pair of drivers, but which it is believed may be permitted and used with advantage under this arrangement, on a good, substantial road. The same pressure of steam (80 pounds per square inch) acting on the pistons in the propelling cylinders, will enable the engine to exert a force of traction of about 5000 pounds, while the 22,500 pounds pressure, or weight of the driving wheels on the rails, will afford a fair practical amount of adhesion for this maximum force of traction. When steam of 60 pounds pressure per square inch is acting in the propelling cylinders, the force of traction of the engine will be about 3,740 pounds, while the same pressure in the adhesion cylinders will make the entire weight on the driving wheels of the engine about 18,700 pounds, which weight on the driving wheels, though less in amount than in the preceding case, is sufficient to afford the adhesion necessary to the force of 3,740 pounds traction, which is also less than in the preceding case. When steam of 40 pounds pressure per square inch is acting in the propelling cylinders, the force of traction of the engine will be about 2,385 pounds, while the same pressure of steam in the adhesion cylinders will make the entire weight on the driving wheels about 14,900 pounds. This weight on the drivers, though less than in either of the above two cases, will afford sufficient adhesion for the force of traction, (2,383 pounds due to the 40 pounds steam acting in the main cylinders); again, when steam of 20 pounds pressure per square inch is acting in the propelling cylinders, the force of traction of the engine will be about 1,039 pounds, while the same pressure of steam in the adhesion cylinders will make the entire weight on the driving wheels about 11,100 pounds. This weight on the driving wheels, though still less than either of the cases before stated, will give adhesion quite sufficient for the occasion, the pull of the engine being less than in any of the cases before stated.
- Agreeable to the foregoing amounts of tractive force and the weight on the driving wheels of the engine here represented, when 80 pounds pressure of steam per square inch is acting on the pistons in the respective sets of cylinders, there is $4\frac{1}{2}$ pounds pressure or weight on the driving wheels upon the rails

for each pound of tractive force of the engine; when 60 pounds pressure of steam is acting in the two sets of cylinders, the pressure on the drivers upon the rails of the road is 5 pounds for each pound of tractive force of the engine; when 40 pounds pressure of steam is acting, the weight on the driving wheels is $6\frac{1}{2}$ pounds for each pound of tractive force of the engine; and with 20 pounds, the pressure of the drivers upon the rails is $10\frac{6}{7}$ pounds for each pound of tractive force of the engine. This is advantageous as will appear from what immediately follows.

The amount of adhesion of the driving wheels of an engine to the rails is varied by more or less moisture or dirt upon the rails, and by other circumstances; it is therefore difficult to determine the exact amount of weight required on the driving wheels of an engine to furnish a given or definite amount of adhesion. Consequently to guard sufficiently against the slipping of the driving wheels some surplus weight on them is required above that, which would be sufficient in most cases for a given force of traction. When the weight on each driving wheel of this plan of engine is the greatest, this surplus weight should be applied most sparingly, because the road is then in most danger of being injured by it, and because the speed of the engine is then more likely to be such, as to enable the adhesion in extreme exigencies to be increased by the use of sand, as now generally practiced; but as the total weight on the driving wheels is diminished, this surplus weight may be more abundantly admitted, for the total weight being less, the injury to the road is less. This being the case, and as it is desirable that the slipping of the wheels should be as fully guarded against by weight on the rails, as is consistent with a due regard to the preservation of the road, and more especially at such speeds as render it difficult or impracticable to use sand, the increasing surplus weight with the diminishing total weight on the drivers is advantageous.

It will be observed that with 20 pounds pressure of steam in the cylinders the traction of the engine (1,039 pounds) is sufficient to propel an ordinary passenger train over a considerable portion of a good road, and that while this is the case the weight on the one pair of driving wheels (11,100 pounds) is about one fifth the entire weight of the engine, or the same in amount to the weight borne by one of the four pairs of truck-wheels; making about an equal distribution of the weight on all ten of the wheels, and no important increase of pressure or weight on the driving wheels will take place except it be required by the greater resistance of the load or train, and then such increase will be in accordance, or very nearly so with the requirements of each particular case, and

when the increased pressure on the driving wheels is no longer required, it will cease to operate. The result is, that the aggregate weight on the driving wheels of this plan of engine is very much less, in proportion to the aggregate work which can be performed by it, than hereto. The accomplishing of this by means of varying the steam pressure upon the plungers or pistons in the adhesion cylinders, or by varying the force with which the steam acts to press the driving wheels down to the rails of the road, is believed to be entirely new, and is intended to be claimed as such.

15 In the several statements here made of the relative force of traction and power of adhesion of the engine, when steam of the same elastic force is acting in the respective sets of cylinders, the results given are derived from calculation, and are believed to be about what will be experienced in practice, or at least sufficiently near it, to answer the present purpose, which is to illustrate one of the features of this invention.

20 When the resistance to motion of the engine and train is such as to require the full force of traction of the engine to overcome it, the throttle valve is opened to such extent as will allow as nearly as practicable the full pressure of steam in the boiler to act upon the pistons of the main or propelling cylinders; the same opening of the throttle valve causes steam of equal pressure to act upon the plungers of the small or adhesion cylinders, which at the same time give the adhesion required for the full exercise of the tractive power of the engine.

25 In the practical working of an engine the average traction required to draw its load is much less than that which the engine is required to exert when starting its load, or taking over hard parts of the road; and as the resistance of the train or traction which the engine is required to exert varies, so the effective pressure of steam acting on the pistons varies in the same ratio. If the pressure of steam in the boiler, per square inch, is greater than that which 30 would be necessary in the propelling cylinders to take a given load at a given speed, and if the generation of steam is sufficiently rapid to maintain the pressure in the boiler above what is required in the cylinders, the 35 steam is partially restrained, or wire drawn, in its passage to the cylinders, by means of the throttle valve, and enough only is allowed to pass through the steam pipe into the cylinders to maintain the requisite 40 degree of speed. When the valve has been so adjusted as to accomplish this, if the resistance of the trains then becomes less from the character of the road or other cause, in order to maintain the same speed, the 45 throttle valve must be operated so as still

further to impede the flow of steam into the pipe leading to the cylinders, and thus reduce the pressure of the steam in the pipe, and consequently the effective pressure in the cylinders, in proportion to the diminished resistance on the load. If the throttle valve be not so operated when the resistance to the progress of the train becomes less, an increase in the speed of the engine follows; while the speed is being accelerated 50 the *vis inertiae* of the moving mass forms a part of the resistance until the speed becomes uniform, and an equilibrium is established between the pressure of steam in the propelling cylinders and the resistance of the train. When the resistance to the progress of the train is increased, the throttle valve is opened so as to admit the steam more freely into the steam pipe leading to the cylinders, otherwise the speed of the engine becomes diminished, and in either case the pressure of the steam in the steam pipe and in the cylinders becomes greater in proportion as the resistance is increased. From this it follows, that when a free communication is formed between the adhesion cylinders and steam pipe leading through the throttle valve to the propelling cylinders as before described, the pressure of steam per square inch in the adhesion cylinders varies with that in the propelling cylinders, and the weight thrown upon the driving wheels by means of the steam acting in the adhesion cylinders is increased or diminished, and although not precisely 55 in the same ratio or proportion, it is in proportion as before stated, which in practice is believed to be more desirable, thus furnishing at all times the requisite amount of adhesion of the wheels to the rails, for 60 the successful operation of the engine, while the average weight on the driving wheels is much less than that required for the maximum resistance of the load. By this means the maximum weight which may be judiciously 65 placed upon any one driving wheel is increased, while the aggregate injury done to the road is diminished. The maximum weight being but occasionally employed and generally at slow speed it may be greater than 70 when it remains constantly on the wheels, and its injurious effects on the road are increased by rapid speed; this favors the use of a single pair of driving wheels, which is important for engines intended for fast 75 speeds. The use of one pair of driving wheels is favorable to their being made large, and to steady movement of the engine and absence from derangements of parts consequent on rapid speed.

80 The application of steam to press down the driving wheels and thus obtain adhesion as described, is not only useful for the purposes before mentioned, but it serves as a most perfect spring to relieve the engine 85

from shocks and jolts occasioned by inequalities of the road. It differs from steel, india-rubber, air, or other similar springs, by the greater uniformity with which a given weight upon the wheels is preserved, while the engine is passing over inequalities of road, and oscillating in different directions; steel and other springs undergo a greater degree of variation in their stiffness when acted upon by such inequalities of the road or oscillation of the engine. The result of which is, that the vertical and other movement or vibration of the engine is restrained within practical limits by the alternate increase and diminution of stiffness in the springs, but this necessarily involves more and less pressure upon each individual wheel, and even upon all the wheels collectively, at particular moments. The steam spring, with the entire steam chamber of the boiler as its fountain, varies in tension or stiffness very little if at all, and therefore would be unfit to be applied to all the wheels of an engine. But when in combination with steel or other springs having the property of varying in stiffness, as herein described, the result is, that the weight on the wheels to which it is applied is less varied by disturbing causes than by the modes before practiced. For the driving wheels of engines this is important in as much as the available adhesion is increased thereby. Again it is desirable that engines intended for fast speed should have as few driving wheels as is practicable, and this is an inducement to put the greatest weight on each driving wheel, which a due regard to the preservation of the road will admit. This object is favored by the use of the steam spring in combination with the steel or other springs as herein specified, because of this greatest weight being less liable to increase the injurious effects upon the road by the fluctuations in the vertical pressure upon the rails. This advantage as well as the one last mentioned, attaches to the steam spring and accompanying arrangements as described, whether the cylinders which give effect to the spring, be supplied with steam direct from the boiler, or from the pipe leading through the throttle valve to the propelling cylinders, as herein set forth. It is true that some of the wheels supporting the engine are subject to fluctuation in their pressure upon the rails, from the causes before stated, and from which the driving wheels are relieved by steam springs; but the bearing wheels may be, and are to be increased in number so that the weight upon each wheel may be so reduced as to allow of this fluctuation being borne by the bearing wheels rather than by the driving wheels, upon which a large weight is necessarily concentrated for the purpose set forth.

When the communication between the

boiler and the adhesion cylinders is direct and not pressing through the throttle valve and pipe leading to the main cylinders, water from the boiler may pass into the adhesion cylinders instead of steam and the effect will be the same, provided the opening between the boiler and cylinders is large enough to allow the water to flow freely, the required elasticity being derived from the steam above the water in the boiler.

An account is given in Nichols Woods' *Treatise on Railroads*, first American from second English edition, pages 135-136, of a locomotive engine having cylinders with pistons in them placed over each of the journals of the axles of the engine, the rods from these pistons pressed upon the chairs that rested on the axles of the wheels on which the carriage moved. The account says: "When therefore the steam presses upon the pistons the weight is transmitted to the axles by the piston rods and the reaction of that pressure takes as much weight off the engine, if therefore the cylinders are of sufficient area, so that the pressure of the steam upon the whole of the pistons is equal to the weight of the engine, the engine will be lifted up, as it were, or entirely supported by steam, which thus forms a kind of spring, of the nicest elasticity." The account further says: "The application of the steam-bearing cylinders divided the weight equally upon the four wheels, and, if necessary, upon six wheels, as shown in Fig. IV, Plate VI, and thus causes one frame to be sufficient, and consequently simplified."

The drawing just referred to represents the side view of a locomotive engine with six wheels of the same size. The middle pair are bearing wheels only, the other two pairs are driving wheels. The drawing indicates the employment of steam springs at each of the journals of the bearing as well as the driving wheels, no other springs are represented or spoken of in the descriptive account of this engine. In an arrangement like this where steam springs only are employed, it would be difficult, if not impracticable, to regulate or maintain the pressure of steam in the spring cylinders, so as to support the entire weight of the boiler and its immediate attachment, and to keep the whole suspended on the springs at the proper elevation above the rails. If this perfect equilibrium or equal balance between the load and the springs should be had at any particular moment, and the load on the springs was but slightly increased by the introduction of more water or fuel into the boiler and otherwise, the result would be that one or both ends of the boiler would settle down until a chock or bearing capable of supporting so much of the weight not balanced by the steam spring was reached, and this would be the case even though the

settling down was continued through a much longer range than would be admissible in practice.

Results similar to these just mentioned, 5 take place when the pressure of steam per square inch in the boiler is varied without the load on the springs being varied; again, the load resting on the steam springs is not checked in its vertical and lateral vibrations 10 consequent upon the action of the engine, for the strength or stiffness of these springs is not increased or diminished by greater or less depressions. These difficulties in the use of steam springs as applied to all the 15 wheels of an engine, is remedied by the use of steel springs and steam springs in combination with each other.

When the steel springs of an engine are of sufficient strength to support the greatest 20 weight which they may be subjected to, any variation of the weight of the load resting upon them which may occur in practice, is attended with only a slight elevation or depression of the boiler and other parts resting 25 on the springs, while the entire weight designed to be supported on the springs continues to be supported. The vertical and other vibrations of the parts of the engine resting on the steel springs is checked or restrained 30 within narrow or practicable limits by the action of the springs themselves, and without the aid of chocks, these springs reacting with more or less energy as they are subjected to more or less tension by the inequalities 35 of the road. Air, india-rubber, and perhaps some other springs adapt themselves to the variations in the load in a similar manner to that of the steel springs, and may therefore be used instead of them.

40 While steel, air, and india-rubber springs as above set forth are better adapted for use in locomotive engines than steam springs, when applied to all the wheels of an engine, the two description of springs may be used 45 advantageously together or in connection with each other, in passenger or other engines, when a portion only of the wheels are drivers. The steam spring being used for transmitting weight to the journals of the 50 driving wheel axle, and the steel, air, india-rubber, or other similar springs being used to support the weight resting on the journals of the bearing wheel axles.

55 In such arrangements of bearing and driving wheels, and springs, the bearing wheels should be sufficient in number to support the entire weight of the boiler and its attachments, without there being more weight on any one wheel, than a due regard 60 for the preservation of the road, will warrant. The bearing wheels which receive the weight of the boiler &c. through the steel, air, india-rubber, or other similar springs, are to be placed under each end of the boiler 65 or the engine, and should have such position

and arrangement as will distribute the weight of the boiler and its attachments equally upon all the said bearing wheels. The driving wheels are placed between the sets of bearing wheels supporting their respective ends of boiler, and care should be taken that the driving wheels are placed in such position to the sets of bearing wheels, that the weight which is thrown upon the driving wheels by the steam in the adhesion 70 cylinders, shall be taken from the respective bearing wheels in such proportion as to leave, as nearly as practicable, an equal weight on each of the said bearing wheels. 75

The side view of the engine Fig. 1, hereto 80 annexed furnishes an illustration of this arrangement and shows a position of wheels and springs under a boiler, and a number of bearing wheels, which it is believed will answer well in practice on a good substantial 85 road, when the entire weight of the engine does not exceed 25 tons. If this engine is to be used on a less substantial road, or the weight of the engine being materially increased, more bearing wheels should be 90 placed under it, and six or eight wheel trucks may be used under each end of the engine instead of four wheel trucks, and be made to swivel on their centers in like manner to the single or four wheeled trucks; 95 and for a better distribution of the weight on the road, four or more driving wheels may be placed between the trucks or bearing wheels, and used instead of two as here shown. In the case where four driving 100 wheels are used, the adhesion cylinders may be placed midway between the axles of said drivers, and the downward pressure of the steam may be distributed among the wheels by means of an equalizing beam; or four, or 105 more adhesion cylinders may be used, one placed over each journal, as arranged for a single pair of drivers.

In order that the objects here had in view may be carried out or realized to a still 110 greater extent a second set of adhesion cylinders may be placed immediately over those before described, and so arranged as to press the propelling wheels to the rails with a force additional to that of the lower sets of 115 adhesion cylinders, as occasion may require; the steam pressure being made to operate or not on these cylinders at the discretion of the engine-man. A mode of carrying out this, is represented in Figs. 1 and 2. The 120 second set of adhesion cylinders are shown at R, R, R, these with their cup formed pistons, stuffing boxes, &c., are like the first or lower set hereinbefore described, except that they are smaller; being in diameter 125 about $7\frac{3}{4}$ inches, which makes the area of these pistons about one half that of the lower set. They are attached to the lower cylinders by the bolts L, L, Fig. 1. The piston rods K, K, Fig. 2, through the me- 130

dium of which the downward thrust of these auxiliary cylinders is exerted, pass down through the stuffing box at *m*, *m*, Fig. 2, and take bearing on the top of the piston of the 5 lower adhesion cylinders, immediately over the rods or pistons which transmit the power to the driving wheel boxes; thus the two sets of cylinders act in conjunction when ever steam is acting on both sets. Steam is let 10 into these cylinders by means of the pipes *n*, *n*, Figs. 1 and 2, directly from the boiler, or it may be from the lower sets of adhesion cylinders. At *o*, *o*, Fig. 2, are stop cocks to be operated by the engine-man, so that he 15 may use the power of these cylinders to produce adhesion, only when occasion may require it, such as: starting a train, a slippery state of the road, or for other similar causes, and relieve the road from the increased 20 stress, as soon, as the occasion for it shall cease. The handles of these stop cocks are connected together by the rod *z*, Fig. 2, so that they may be operated on simultaneously and by one act of the engine-man. In like 25 manner a third or more sets of adhesion cylinders may be placed over the others, and thus give still greater range and action to the force with which the wheels may be pressed to the rails, at the moment required 30 for adhesion.

Most engines of ordinary construction vary the weight upon their driving wheels, as the pressure of the steam in their ordinary propelling cylinders is varied. This 35 may proceed from the coupling bar between the engine and tender being oblique to the horizon, or from its attachment to the engine being above the line of the rails, or from the power being transmitted from the propelling cylinders to the driving wheels on a 40 line oblique or at right angle to the horizon,

and it may be from other causes. This variation of the weight on the driving wheels of engines, by the steam pressure, operating through the medium of the ordinary propelling cylinders, whether incidentally, or by design, or whether operating advantageously, or otherwise, has long been well known, and is not intended to be claimed. 45

What I claim as my invention and desire 50 to secure by Letters Patent, is—

1. The use of steam springs for the support of the weight carried by the driving wheels of a locomotive engine, in combination with bearing or supporting wheels 55 placed both before and behind the aforesaid driving wheels; which bearing wheels support a portion of the weight of the engine, through the medium of steel, air, india-rubber, or other springs, possessing the properties herein described, as belonging to steel springs as distinguished from steam springs; for the purpose set forth in the specification. 60

2. I also claim the employment of steam springs, or steam pressure operating separately from the propelling cylinders, for the purpose of varying the pressure of the driving wheels of a locomotive engine upon the rail of the road, in combination with bearing or supporting wheels placed both before and 70 behind the aforesaid driving wheels, which bearing wheels support a portion of the weight of the engine, through the medium of steel, air, india-rubber, or other springs, possessing the properties herein described, 75 belonging to steel springs, as distinguished from steam springs; for the purpose set forth in the specification.
